United States Patent Office

Des. 203,854
Patented Feb. 22, 1966

203,854

COFFEE MAKER

David Douglas, 1332 S. 26th St., Manitowoc, Wis.

Filed June 4, 1964, Ser. No. 80,284

Term of patent 14 years

(Cl. D44—26)

FIG. 3

FIG. 1

FIG. 4

FIG. 2

FIG. 1 is a perspective view of a coffee maker showing my new design, with a cup shown in broken lines for purposes of illustration only;

FIG. 2 is a side elevational view of the coffee maker shown in FIG. 1;

FIG. 3 is a top plan view of the coffee maker; and

FIG. 4 is a bottom plan view of the coffee maker.

I claim:

The ornamental design for a coffee maker, substantially as shown and described.
